UNITED STATES PATENT OFFICE.

CHARLES HUGO, OF WORCESTER, MASSACHUSETTS, ASSIGNOR TO THE M. J. WHITTALL ASSOCIATES, A VOLUNTARY ASSOCIATION OF MASSACHUSETTS.

PATTERN-FEED MECHANISM FOR LOOMS.

Application filed June 7, 1921. Serial No. 475,821.

To all whom it may concern:

Be it known that I, CHARLES HUGO, a citizen of the United States, residing at Worcester, in the county of Worcester and State 5 of Massachusetts, have invented a new and useful Pattern-Feed Mechanism for Looms, of which the following is a specification.

This invention relates to improvements in pattern feed mechanism for looms by which 10 the direction and extent of the pattern chain feed may be varied. In a prior Patent No. 981,762 issued to me January 17, 1911, I have fully set forth the advantages to be derived from advancing the pattern 15 cards in a carpet loom or other similar loom two spaces in either direction at each feeding movement.

It is the object of my present invention to provide means by which a pattern chain 20 may be advanced one, two, three or more spaces in either direction at each operation of the feeding mechanism. Movement of the pattern cards by three's is desirable when three different patterns are used, such 25 as a border pattern, an end body pattern and a center body pattern. It will be understood that any one of the three patterns may be repeated in either forward or reverse direction as often as is desired. 30 With this general object in view, important features of my invention relate to improved feeding devices by which a pattern cylinder may be advanced in either direction either one, two or three spaces as desired, 35 to means for controlling the amount of feed, and to means for yieldingly holding the pattern cylinder from movement when in normal position but for releasing the cylinder during the feeding operation.

40 My invention further relates to arrangements and combinations of parts which will be hereinafter described and more particularly pointed out in the appended claims.

A preferred form of my invention is 45 shown in the drawings in which—

Fig. 1 is a side elevation of my improved pattern feeding mechanism;

Fig. 2 is a partial plan view thereof;

Fig. 3 is a side elevation, partly in section, 50 taken along the line 3—3 in Fig. 2;

Fig. 4 is a similar view taken along the line 4—4 in Fig. 2;

Fig. 5 is also a side elevation of the parts shown in Fig. 2 but in a different position;

Fig. 6 is a plan view of the yielding locking device;

Fig. 7 is a side elevation of the locking device together with its actuating mechanism, and

Fig. 8 is a detail view of the means for 60 moving the locking device.

Referring to Fig. 1, I have shown a jacquard frame 10 having the usual lifter board 11 (Fig. 2) and needles 12 controlled by pattern cards 13 which are advanced and rendered operative by a pattern cylinder 14. 65 As shown in the drawings, the cylinder 14 is provided with six flat faces against which the cards rest and is also provided with six projecting studs 15 which are engaged by 70 the end 16 (Fig. 4) of the locking slide 17. A coil spring 18 (Fig. 6) normally forces the slide against two of the studs, and thus yieldingly positions the cylinder with one of its faces presented to the ends of the needles 75 12.

The cylinder 14 is mounted on a shaft 19 supported in bearings 20 mounted on sliding bars 21. A gear 22 is rotatably mounted at the end of one of the sliding bars 21 and 80 meshes with a pinion 23 secured to the end of the shaft 19. As shown herein, the gear 22 is three times the size of the pinion 23.

The slide bars 21 are mounted in fixed bearings on the frame 10 and their left hand 85 ends as viewed in Fig. 1 are provided with studs 24 each extending through a slot 25 in an arm 26 fixed to a rock shaft 27. An actuating arm 28 is also secured to the rock shaft 27 and is normally held against an 90 adjustable stop 29 by a spring 30. The arm 28 is intermittently lifted by engagement with a shoulder 31 in a forked rod 32. The rod 32 is connected at its lower end to an arm 33 which, in turn, is connected by a 95 link 34 to a lever 35 having a cam roll 36 engaging a continuously rotating cam 37. By this mechanism the rod 32 is raised intermittently and during the upper portion of its travel engages the arm 28 and is thus 100 effective through the arms 26 to move the guide bars 21, thus carrying the cylinder 14 outward, away from the ends of the jacquard needles. The arm 33 is also con-

connected through its pivot shaft and connections not shown to operate the lifter board 11.

During this outward movement, the cylinder is advanced by feeding mechanism about to be described. The gear 22 is provided with a series of lateral studs or pins 38 adapted to be engaged by the hook-shaped ends of feed pawls 39 and 40. These pawls are made in two parts, as best shown in Fig. 5, and a bolt and slot connection is provided by which the length of the pawls may be adjusted. The pawls are pivoted on a cross bar 41 (Fig. 1) mounted on a slide 42 and they are connected together by a link 43. The lower pawl 40 is provided with a rearwardly and upwardly extending arm 43' to which a cord 44 and hook 45 may be attached.

The normal position of the pawls is shown in Fig. 1, with the upper pawl 39 operative, but this position may be reversed by placing a weight on the hook 45 sufficient to overcome the weight of the pawls, thus swinging the lower pawl 40 to operative position. A bell crank 46 is mounted on the frame 10 and has a bolt and slot connection with the slide 42. A spring 47 normally holds the parts yieldingly in the position shown in Fig. 1, further movement being prevented by one of the slide bearings. A stud 48 on the arm 33 engages the horizontal arm of the bell crank 46 and moves the slide 42 and pawls 39 and 40 to the left as the arm 33 approaches its upper limit of movement.

A chain 50 (Fig. 7) connects the locking device slide 17 to an arm 51 on a cross shaft 52 having bearings in the frame 10. An arm 53 on said shaft is connected by a link 54 to a lever 55 (Fig. 8) having a cam roll 56 engaged by a continuously rotating cam 57. The slides 21 which support the cylinder are provided with adjustable brackets 58 (Fig. 6) to which is secured the cross board 59 which resets the needles 12.

Having described the construction of my improved feed mechanism I will now describe its operation. Starting with the parts in the position shown in Fig. 1, the cam 37 will raise the link 34 and arm 33, carrying upward the lifter board 11 and also the rod 32. The shoulder 31 of the rod 32 presently engages the arm 28, causing swinging movement of the arm 26 to advance the slides 21 supporting the cylinder 14. At the same time the cross board 59 resets the needles 12.

As the cylinder 14 is moved away from the needles, the cam 57 (Fig. 8) moves the arm 51 (Fig. 7) to the left and withdraws the head 16 of the holding device 17 from the studs 15 in the end of the cylinder. As the upward movement of the arm 33 continues, the stud 48 on the arm 33 engages the bell crank 46 and moves the slide 42 to

the left (in Fig. 1). The combined movement of the cylinder and slide in opposite directions causes one of the pawls 39 or 40 to engage the pin teeth 38 and thus partially rotate the gear 22.

The gear ratio between the gear 22 and the pinion 23 causes a greatly increased angular movement of the cylinder 14, the movement of the cylinder herein shown being three times the movement of the gear. By thus combining a movement of the cylinder to the right with a movement of the feed pawl to the left, a wide range of movement is available and it is easily possible to advance the cylinder three spaces or 180° at each feeding movement. By changing the length of the pawls 39 and 40 this movement may be reduced to an advance of only one or two spaces instead of three spaces if so desired.

The head 16 of the locking device 17 is held away from the stud 15 in the cylinder until the feeding movement has been completed, after which the cam 57 releases the locking device and the spring 18 advances the same until the end 16 thereof yieldingly engages the studs before the return movement of the cylinder. The usual hand lever 60 and cord 61 (Fig. 1) are provided for advancing the cylinder one or more spaces when it is desired to change from one pattern to another.

Having thus described my invention it will be evident that changes and modifications can be made therein by those skilled in the art within the spirit and scope thereof as set forth in the claims, and I do not wish to be otherwise limited to the details herein disclosed but what I claim is:—

1. In a loom, a pattern cylinder having a plurality of flat faces, a single feeding device effective to advance said cylinder one half of a cylinder revolution at each single intermittent actuation of said feeding device, and means to reduce the angular movement resultant from each such actuation of said feeding device to the angular equivalent of a less number of cylinder faces.

2. In a loom, a pattern feed mechanism comprising a pattern cylinder, a device to yieldingly hold said cylinder from movement, means to slide said cylinder outward during the cylinder feed, and means to hold said device from movement with said cylinder during the cylinder feed and to thereafter restore said device to holding position before the return of said cylinder to initial position.

3. In a loom, a pattern cylinder, a feeding pawl, means to move said pattern cylinder from normal position in one direction, means to advance said feed pawl from normal position in the opposite direction, and means to hold said cylinder yieldingly in position.

4. In a loom, a pattern cylinder, a feeding

- 5 pawl, means to move said pattern cylinder from normal position in one direction, means to advance said feed pawl from normal position in the opposite direction, and
means to hold said cylinder yieldingly in position, said holding means being inoperative during the angular movement of the cylinder.
- 10 5. In a loom, a pattern feed mechanism comprising a pattern cylinder having a plurality of flat faces, a pinion on said cylinder, a substantially larger gear meshing with said pinion, a feed pawl and ratchet effective to intermittently advance said gear and feed
15 said cylinder through an angle equivalent to one cylinder face, means to move said feed pawl uniformly with an excess feeding movement, and means to increase the angular movement of said cylinder resultant from each such uniform actuation of said feeding pawl to the angular equivalent of more than one cylinder face.
6. In a loom, a pattern feed mechanism comprising a pattern cylinder, a pinion on said cylinder, a substantially larger gear meshing with said pinion, feed pawls for said gear, separate sliding supports for said cylinder and feed pawls, and means to move said supports in opposite directions to give said pawls an extensive operating movement relative to said cylinder.

In testimony whereof I have hereunto affixed my signature.

CHARLES HUGO.
